BUILDING AIR MONITOR

Howard C. Eberline, Santa Fe, N. Mex., assignor to Eberline Instrument Corporation, Santa Fe, N. Mex.

Filed June 3, 1964, Ser. No. 80,271

Term of patent 3½ years

(Cl. D52—6)

FIG. 1 is a perspective view of a building air monitor, showing my new design;

FIG. 2, a side elevation;

FIG. 3, a top plan;

FIG. 4, a rear elevation; and

FIG. 5, a bottom view.

The undisclosed side of the building air monitor is substantially the same in appearance as the side shown.

I claim:

The ornamental design for a building air monitor, as shown and described.
